UNITED STATES PATENT OFFICE.

JOHN W. THARP, OF QUINCY, ILLINOIS.

CONVERTIBLE DRESSER TRUNK.

Application filed June 20, 1927. Serial No. 199,932.

My invention relates to improvements in convertible dresser trunks, and has for its primary object a trunk which can be readily converted into a dresser.

5 A further object is to construct a convertible trunk which is provided with a hinged lid containing a mirror and which is especially adapted for use on automobiles, taking the place of the ordinary trunk customarily carried by such vehicles at their rear end, and which when removed from the automobile can be readily converted into a dresser.

10 A still further object is to construct a convertible trunk in which the articles carried by said trunk are deposited in drawers, which are automatically locked when the lid is lowered and which can only be opened when the lid is raised. This makes my device especially useful when used for touring purposes as not only is a trunk provided in which clothing can be readily carried, but the trunk can be quickly converted into a dresser thereby making it especially useful for camping purposes.

In the drawings:

Fig. 1 is a front view of my device when arranged as a trunk;

Fig. 2 is a side view of the same;

30 Fig. 3 is a bottom plan view showing the manner of collapsing the supporting legs;

Fig. 4 is a front elevation showing my device arranged as a dresser;

Fig. 5 is a side elevation of the same;

35 Fig. 6 is a top plan view with the lid or cover detached;

Fig. 7 is an enlarged fragmental cross section illustrating the manner of locking the drawers when the lid or cover is closed;

40 Fig. 8 is a fragmental perspective view of the locking means;

Fig. 9 is an edge view of one of the supporting legs; and

Fig. 10 is a side view of the same.

45 In the construction of my device I employ a casing comprising a front 11, a back 12, and side members 13. The casing is provided with a bottom 14 and with a top 15. The bottom 14 is recessed or set up above the lower edge of the front, back and sides so as to provide a space for the supporting legs 16 when in collapsed position.

Secured to the sides 13 are a plurality of

spaced apart slides 17 which slidably support drawers 18. These drawers are provided with knobs 19^a so that the same can be readily pulled out or pushed in. However in place of knobs any other means by which the drawers can be pulled out may be employed.

The top 15 is located at some distance below the upper edge of the sides 13 and back 12, the front being unobstructed. Carried by the sides 13 and positioned above the top 15 are slides 19 in which a board or top 20 is fitted in such a manner that it can be easily removed. On one face of the top 20 is provided a resilient padding 21, such as felt or the like, the purpose of which will be explained in detail later. Secured to the back 12 are hinges 22, these hinges also being secured to the lid or cover 23, which lid is provided with a flange 24 so that when the lid is closed, the lower edge of the flange will rest on the top 15 and prevent any movement of the slide 20.

75 Carried by the lid 23 is a frame 25, which surrounds a mirror 26 and between the back of the mirror and the lid or cover 23 I place padding or resilient material 27.

Pivotal carried by the bottom 14 are legs 80 16, which are held in position by means of studs 29 passing through ears or brackets 30, which brackets are secured to the bottom 14 in any well known manner. The legs 16 are provided with furniture slides 31, which, 85 when the legs are in collapsed position, project below the lower edge of the trunk so as to permit it to move freely. The legs are tied together in pairs by means of cross rods or bars 32, which will tend to stiffen them when 90 in extended position, as illustrated in Fig. 5. In order to afford a support for the legs I have provided blocks 33, which are located at each corner of the trunk and against which the legs abut when in extended position, and, 95 in order to provide a support for the legs when in collapsed position, I employ blocks 34. These blocks are of such width or thickness that when the legs 28 are in the position indicated in Fig. 3 that they will bind 100 against the blocks thus frictionally holding them in position when the trunk is lifted. They also act as stiffeners for the legs when the trunk is moved on the slides, co-acting in this instance with the stiffener 32.

105 In order to keep the lid or cover down

straps 35 are made use of and my device can also be supplied with a lock, such as is ordinarily used on trunks or with a hasp and pad lock. This however I have not shown as it is a well known construction.

The slide 20 is provided with a cutaway portion 36 through which the upper end 37 of the drawer locking means extends. This drawer locking means consists of a rod 38 which has extensions 39 integral therewith. These extensions pass through ears 40 carried by the back 12 and also through ears 41 carried by the back of the drawers 18. A spring 42 is employed which surrounds one 15 of the extensions 39 in such a manner that it will have a tendency to lift the rod 28 when the lid or cover 23 is raised. The upward movement of the rod is limited by means of a stop 43. It will be noted from Fig. 7 that the locking means 38 also pass through the top 15. In order to prevent the lid or cover from being thrown too far back I employ a restraining means 44. This may be either a chain as illustrated in Figs. 4 and 5 or any 20 other well known restraining means and therefore I do not desire to limit myself thereto, nor do I desire to limit myself to the peculiar type of furniture slides disclosed in Figs. 9 and 10, as in place of the ordinary slide 25 I may employ either rollers, casters or similar rolling means. The peculiar type of locking mechanism for the drawers may also be varied without departing from the spirit of my invention.

During the shipment or traveling of the trunk, the device is in the position as shown in Figs. 1 and 2, that is with the lid down. When in this position the lid or cover contacts with the end 37 of the locking means 38 moving it downward into the position shown in Fig. 7 so that the projections 39 will pass through the ears 41 and 40 thereby preventing any accidental opening of the drawers.

When the device is to be used as a dresser 45 the straps 35 are removed and the locking means for the lid, if any has been provided, is unlocked and the lid or cover raised. This raising of the lid permits the spring 42 to move the locking means upward thereby unlocking all of the drawers so that they can be pulled out and access had to their contents, it being understood, of course, that the legs 16 have been preferably moved into the position illustrated in Figs. 4 and 5, the restraining members 44 preventing the lid from moving too far back. After this has been done the slide 20 is withdrawn and reversed so that the padding material will be on the underneath side, sufficient space having been

left between the top 15 and the slide to accommodate this padding material.

When it is desired to again close the trunk, the slide is reversed so as to bring the padding material uppermost, the drawers pushed all the way in, the lid or cover lowered. 65 When in this position, as illustrated in Fig. 7, the mirror will be between two elastic pads so that there will be very little danger of it becoming broken; at the same time the chains or restraining members 44 being secured outside of the mirror will not in any way interfere therewith. The legs are then collapsed and the straps or locking device for the lid operated and the trunk is ready for shipment.

My device may be either constructed of wood or of sheet metal, the latter being preferable especially when used for automobile trunks.

Having fully described my invention, what I claim is:—

1. A convertible dresser trunk comprising a casing, drawers slidably mounted in said casing, a hinged lid having a mirror secured to its underneath surface for said casing, means located in said casing and co-operating with said drawers whereby the same are automatically locked when said lid is closed and unlocked when said lid is opened, a sliding top carried by said casing and having a body of resilient material located on one face thereof, said material adapted to contact with said mirror when said lid is closed, and folding legs carried by the bottom of said casing, said legs being provided on one face with means whereby said trunk can be readily moved when the legs are in folded position.

2. A convertible dresser trunk comprising a casing, drawers slidably mounted in said casing, a hinged lid having a mirror secured to its underneath surface for said casing, means located in said casing and co-operating with said drawers whereby the same are automatically locked when said lid is closed and unlocked when said lid is opened, a sliding top carried by said casing and having a body of resilient material located on one face thereof, said material adapted to contact with said mirror when said lid is closed, folding legs carried by the bottom of said casing, said legs being provided on one face with means whereby said trunk can be readily moved when the legs are in folded position, and means for supporting said lid when the same is opened.

In testimony whereof I have affixed my signature.

JOHN W. THARP.
